US00D981731S

(12) **United States Design Patent** (10) **Patent No.:** **US D981,731 S**
Zemel et al. (45) **Date of Patent:** **** Mar. 28, 2023**

(54) **GRILL BRUSH**(71) Applicant: **Mr. Bar-B-Q Products LLC**,
Hauppauge, NY (US)(72) Inventors: **Marc Zemel**, Hauppauge, NY (US);
Joanne Rudis, Hauppauge, NY (US)(73) Assignee: **Mr. Bar-B-Q Products LLC**,
Hauppauge, NY (US)(***) Term: **15 Years**(21) Appl. No.: **29/825,601**(22) Filed: **Feb. 3, 2022**(51) LOC (14) Cl. **04-01**

(52) U.S. Cl.

Primary Examiner — Keli L Hill(74) *Attorney, Agent, or Firm* — Carter, DeLuca & Farrell
LLP(57) **CLAIM**The ornamental design for a grill brush, as shown and
described.**DESCRIPTION**FIG. 1 is a perspective view of a grill brush in accordance
with the present design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines shown in the drawings illustrate portions of
the grill brush that form no part of the claimed design.**1 Claim, 5 Drawing Sheets**| (56)	References Cited
